WILLIAM LONSDALE, OF ELIZABETH, NEW JERSEY, ASSIGNOR TO WHEELER
CONDENSER AND ENGINEERING COMPANY, OF CARTERET, NEW JERSEY.

ROTATIVE DRY VACUUM-PUMP.

1,370,979.

Specification of Letters Patent.

Patented Mar. 8, 1921.

Application filed May 6, 1920. Serial No. 379,212.

To all whom it may concern:

Be it known that I, WILLIAM LONSDALE, a citizen of the United States, residing at Elizabeth, in the county of Union, State 5 of New Jersey, have invented an Improvement in Rotative Dry Vacuum-Pumps, of which the following is a specification.

This invention relates to a rotative vacuum pump and more particularly to the pump 10 valves and the manner of cooling the same or maintaining the valves and valve ports at a predetermined temperature. Heretofore, much difficulty has been experienced in providing a water or other cooling jacket 15 for the outside of the valve ports of rotative dry vacuum pumps and similar structures, and in fact, so far as I am aware, such cooling jackets are impractical. In the use 20 of the pumps to which this invention relates, difficulty has also been experienced due to the heating of the valves and valve ports and the resultant carbon deposits from the cylinder oils employed to lubricate the pistons of the engines with which the pumps 25 are employed. In the higher grade cylinder oils there is comparatively little carbon deposit, but in the lower grade oils commonly employed the carbon deposit often becomes so excessive as to impair the efficiency of the 30 pump, and the object of my present invention is to overcome this difficulty by employing a structure in which the valves of the pump are cooled by circulating water or other equivalent medium so as to maintain 35 the same at a predetermined and sufficiently low temperature to prevent the volatilization of the cylinder oils in passing through the pump and the consequent carbon deposits which accumulate in the valve ports, 40 whereby it has been found quite possible to use relatively low grade cylinder oils without the accumulation of these deposits. It will be understood that while I have herein shown and described the invention as applicable to rotative dry vacuum pumps the 45 same may be used in compressors and other apparatus where and when occasion may require.

In the drawing:

50 Figure 1 is a sectional view taken through the valve chest of a rotative dry vacuum pump.

Fig. 2 is a transverse section of the valve.

55 Fig. 3 is a longitudinal section of the cooling medium head showing the same in

position at right angles to that illustrated in Fig. 1.

Fig. 4 is a view similar to Fig. 1 showing another form of the invention, and

Fig. 5 is a section of the cooling medium 60 head employed in the structure shown in Fig. 4 but taken at right angles to the position in which this part is illustrated in Fig. 4.

Referring to the drawing and particularly to Figs. 1, 2 and 3, the pump body or a portion thereof is indicated at 10 and the cylinder of the pump at 11. As is customary the pump body is provided with valve chests 12 and 13, the former of which is 70 fitted with a chest head 14 and the latter with a chest head 15.

Centrally the chest head 14 is provided with a bore adapted to receive a tube 16 which, at its inner end, is flanged as indicated at 17 so as to be set into one head of the valve 18 and is secured in position therein by means of screws 18' or otherwise. The tube 16 extends appreciably beyond the face of the chest head 14, and associated with the 80 extension and the chest head I employ a water head and gland 19. This water head and gland 19 may be secured in position in the chest head by means of bolts 20 or otherwise. I also employ a supply pipe 21 for the 85 admission of the cooling water or other cooling medium, and at one end this supply pipe 21 is secured in the water head and gland 19 with the orifice at the end of the supply pipe preferably coincident with the face or 90 end of the water head and gland 19 so that the cooling medium whether water or its equivalent may be supplied from any suitable source to this orifice 22 at this end of the supply pipe. This water head and gland 95 is also provided in the side thereof with an opening 23 which serves as a discharge outlet as will be hereinafter more particularly described. The supply pipe 21 extends entirely through the space in the valve 18 100 longitudinally thereof and at its opposite end is supported or secured in a lug 24 which is adjustably mounted in the opposite head 25 of the valve. At this end of the supply pipe the same is provided with series 105 of openings or holes 26 for the escape of the cooling medium from the supply pipe to the chamber or space within the valve. The valve 18 as is customary in pumps of this type is cylindrical and provided with trans-

110

versely curved walls 27 and 28 with a passage 29 between the same for making communication between the ends of the cylinder for equalizing the pressure at the ends of the piston strokes, and a space 30 providing communication, when the valve is in the correct position, between the inlet to the pump and the cylinder ends, and a space 31 providing communication, when the valve is in proper positions, between the ends of the cylinder and the discharge ports.

In the use of this apparatus, the water or other cooling medium employed is supplied to the pipe 21 through the orifice 22 and passes through the supply pipe to the opposite end of the valve, then flows through the holes 26 in the supply pipe into the chamber in the valve, returning in the opposite direction through this chamber to the space between the supply pipe and the tube 16 so as to be withdrawn from the valve at the outlet or discharge orifice 23.

By reference to Figs. 4 and 5, it will be seen that I may dispense with the supply pipe 21 and provide the gland 19 with a head 32 which has an inlet opening 33 in the side thereof for the cooling medium so that the cooling medium may pass directly through the tube 16 into the chamber in the valve and flow but one way therethrough, being discharged through the opening 34 in the opposite head of the valve and passing through the bore 35 to the discharge outlet 36 in the valve stem 37. Obviously, the same results are obtained in this structure as those described in connection with the preferred form of the invention. It will be equally obvious that the invention is not restricted to the specific structures herein shown and described, as the chamber in the valve may be, for example, partitioned and the water caused to flow through the same in various courses either longitudinally thereof or transversely thereof, or, for a further example, the chamber in the valve might be fitted with banks of tubes in the same manner that certain types of surface condensers are made and the same results obtained without departing from the nature and spirit of the invention.

I claim as my invention:

1. In a rotative dry vacuum pump, a valve chest, a rocker valve having a chamber therein, and means for admitting a cooling medium through the end of the valve chest to the chamber in the valve and withdrawing the cooling medium therefrom.

2. In a rotative dry vacuum pump, a valve chest, a rocker valve having a chamber therein, and means at the same end of the valve chest for admitting a cooling

medium to the chamber in the valve and withdrawing the cooling medium therefrom.

3. In a rotative dry vacuum pump, a body member, a valve chest, a valve adapted to oscillate in the valve chest, a head member connected to the valve chest and provided with means for admitting a cooling medium to the same and through the valve chest into the chamber in the valve, and means for withdrawing the cooling medium from the chamber in the valve in order to maintain the valve at a predetermined temperature.

4. In a rotative dry vacuum pump, a body member, a valve chest, a rocker valve in the valve chest, a head and gland member secured to the valve chest, a supply pipe connected to the head and gland member and extending into a chamber in the valve for admitting a cooling medium thereto, and means for withdrawing the cooling medium from the chamber in the valve in order to maintain the valve at a predetermined temperature.

5. In a rotative dry vacuum pump, a body member, a valve chest, a rocker valve in the valve chest and having a chamber therein, a head and gland member secured to the valve chest, a tubular member mounted in the valve chest, a supply pipe secured in the head and gland member and passing through the said tube into the chamber in the valve for admitting a cooling medium to the chamber in the valve, and means for withdrawing the cooling medium from the chamber in the valve in order to maintain the valve at a predetermined temperature.

6. In a rotative dry vacuum pump, a body member, a valve chest, a rocker valve in the valve chest and having a chamber therein, a head and gland member secured to the valve chest, a tubular member mounted in the valve chest, a supply pipe connected at one end in the said head and gland member extending through the said tube in a position spaced therefrom and through the chamber in the said valve, and a support for the inner end of the said supply pipe in the opposite end of the said valve, the said supply pipe at its inner end being provided with a series of holes whereby the cooling medium after passing through the supply pipe is admitted to the chamber in the valve and is withdrawn therefrom through the space between the supply pipe and the said tube and through an outlet orifice in the said gland head.

Signed by me this 20 day of April, 1920.

WILLIAM LONSDALE,
